UNITED STATES PATENT OFFICE

128,521

DESIGN FOR A TEXTILE FABRIC

Edward Donald Witt, New Canaan, Conn.

Application June 28, 1941, Serial No. 101,794

Term of patent 3½ years

To all whom it may concern:

Be it known that I, Edward Donald Witt, a citizen of the United States of America, residing in New Canaan, county of Fairfield, and State of Connecticut, have invented a new, original, and ornamental Design for a Textile Fabric, of which the following is a specification, reference being had to the accompanying drawing, forming part thereof, wherein the figure of the drawing is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric, substantially as shown and described.

EDWARD DONALD WITT,
